UNITED STATES PATENT OFFICE.

HAROLD WORKMAN, OF GLASGOW, SCOTLAND.

PROJECTION LAMP.

Application filed May 15, 1926, Serial No. 109,446, and in Great Britain May 14, 1925.

This invention relates to motor car head lamps and more definitely speaking to head lamps of the class furnished with a parabolic or approximately parabolic reflector 5 with a concentrated light source, preferably an incandescent electric lamp having a single pillar filament, which is adjusted in position to lie along the axis of the reflector and to extend either backwardly or forwardly from the focus of the reflector.

When such a filament is set so that it extends backwards from the focus along the axis of the parabolic reflector and the upper half of the reflector or lamp front is 15 covered over, a flat topped beam of light will be projected by the lower half of the reflector. In a similar fashion when the filament is set so that it extends forwardly from the focus along the axis of the parabolic reflector and the lower half of the reflector or of the lamp front is covered over, a substantially flat topped beam will 20 also be projected from the upper half of the reflector upon an object at a distance of say 20 feet or more in front of the lamp.

The main object of the present invention is to arrange a motor car head lamp of the class referred to above so as to give a full light beam and yet render it possible for 30 the driver to cut out at will the reflected rising light which forms the upper half of the light beam. The invention further aims at enabling the light so cut out not to be wasted, but to be used to the best advantage, either by adding penetration to the flat topped beam, or preferably by increasing the width of that beam and the illumination of the roadway near to the car, and if desired partly in providing subdued rising light of similar or greater dispersion and much reduced penetration.

With these objects in view, according to the present invention a motor car head lamp of the class already referred to is provided with a movable screen operating within the reflector of the lamp and arranged to be controlled from the driver's seat in such a way that when in one position, which may be termed the "closed" position, the screen forms a hood-shaped cover lying substantially between the light source and one half of the surface of the reflector and when in another position, which may be called the "open" position, the said screen allows the light from the source free access to the whole

or to almost the whole of the said half of the surface of the reflector. The movable screen does not necessarily intercept all the light controlled by it during the passage of the light between the filament and the 60 half of the reflector in question, some light may pass on to the rearward portion of the reflector and be intercepted by the movable screen after the light has been reflected. This state of affairs is intended to be included in the above statement that the screen lies substantially between the light source and one half of the surface of the reflector. The screen is preferably arranged so that when in the "open" position the bulb can be 65 easily removed and replaced without disturbing the screen or its supports or its operating mechanism. The movable screen may be arranged in some forms of lamp in accordance with the invention so that when it is in the "closed" position it covers the 70 upper half of the front of the bulb, thereby cutting out direct rising light from the filament, but this is not necessary as such light does not produce objectionable glare and it 75 is preferably arranged to allow a clear path for such rays through the lamp front. The movable screen in the "closed" position is 80 preferably arranged so that the hood-shaped cover formed by it surrounds the half of the bulb fairly closely at its forward edge, thereby preventing much light from the 85 central portion of the reflector from being projected upwards from within it. For this reason it may be preferable in some constructions to make the higher candle power 90 bulbs of elongated form rather than to increase their diameter. Any members forming part of the movable screen or associated with the movable screen which remain 95 between the light source and the reflector when the screen is in the "open" position, are 100 preferably mounted so that in that position they lie in or near to the vertical axial plane of the reflector. When so situated these parts produce radial shadow bars in a vertical or nearly vertical position in the light beam and these shadow bars can be laterally spread and in effect obliterated by 105 using a vertically grooved or ribbed front glass and when the flat topped beam is projected the definition of its upper edge is not injuriously affected.

Such members should not be arranged to lie in or near to the horizontal axial plane 110

of the reflector as the shadow bars produced by them when so situated cannot be removed by a diffusing front glass in the ordinary way so as to obtain a good full light beam 5 without destroying the definition of the upper edge of the flat topped beam when such is in use, thereby defeating the object of the invention.

In any form of lamp in accordance with 10 the present invention, the movable screen may be operated from the driver's seat by any suitable means such as wires or levers, Bowden wires, electric solenoid and plunger, or by air or other fluid suction or pressure.

15 In order that the invention may be more clearly understood and readily carried into effect, some examples of motor car head lamps in accordance therewith will now be described with reference to the accompanying 20 drawings which illustrate examples of the forms of screen already referred to and in which:—

Figure 1 is a central vertical section of one form of lamp in accordance with the 25 invention showing the reflector, the lamp bulb, the movable screen and its operating mechanism. In this figure the screen is in the closed position;

30 Figure 2 is a similar view with the screen in the open position;

Figure 3 is a vertical section on the line III—III in Figure 2;

35 Figure 4 is a plan view with the reflector in section of a somewhat modified form of lamp in accordance with the invention;

Figure 5 is a central vertical section of the same;

40 Figure 6 is a rear view of Figure 4 with the reflector omitted;

45 Figure 7 is a central vertical section showing yet a third form of lamp in accordance with the invention;

Figure 8 is an elevation of the lamp looked at from the mouth of the reflector;

50 Figure 9 is an elevation of the rear of Figure 7 taken in the direction shown by the arrow and illustrating the operating mechanism; while

Figure 10 is a central vertical section of a fourth form of the lamp;

55 Figure 11 is a plan of the same, and

Figure 12 is a central vertical section of yet a further construction of lamp in accordance with the invention.

60 Referring first of all to Figures 1 to 3, the lamp is shown with a parabolic reflector 1 and with an incandescent lamp 2, the filament 3 of which lies along the axis of the reflector 1 and extends rearwardly from the focus 4 of the reflector. The screen 5 consists of a half barrel or round hood shaped cover having the form of a zone from the centre of a hemisphere, the centre of which hemisphere lies approximately at a point 6 between the centre and rear end of the

filament 3. As illustrated, the screen 5 is adapted when in the "closed" position shown in Figure 1 to screen entirely the upper half of the surface of the reflector 1 from light from the filament 3. The lamp holder 7 is mounted at the inner end of a tubular shell 8 attached to the back of the lamp body 9. The screen 5 is attached to a sliding sleeve 10 which may travel backwards and forwards on the tubular shell 8 up to a collar or flange 11 fixed to the front end of the shell 8 when the screen 5 is in the "closed" position as shown in Figure 1. The flange 11 also constitutes a back reflector 70

75 which is made to reflect the light from the space between the lamp holder and the angular opening through which the movable screen slides and is preferably formed with a curvature about the centre 53, this point being the junction of the lines bisecting the angles between the front end of the filament, the inner and outer edges of the reflector 11 and the front edge of the movable screen 5. This reflector so formed produces a wide spread beam of moderate penetration and adds materially to the near illumination but in such a way that all the rising light rays are cut off and reflected downwards when the movable screen is in the closed position.

80 Alternatively, if the centre of curvature 11 of the back reflector is brought somewhat nearer to the axis of the main reflector rising light will be produced by the back reflector which will not be cut off by the operation of the movable screen.

85 Any means may be provided to keep the half barrel 5 in the correct angular position; for example, a pin or key carried by the shell 8 may engage a slot in the sleeve 10. The reflector 1 is mounted coaxially with the tubular shell 8 and the lamp holder 7 and is cut to admit the movable screen 5. The arrangement is such that the normal position of the screen 5 is the

90 closed position shown in Figure 2 where- 95 in the lamp projects a full or complete beam. Normally the screen is pressed into that position by a helicoidal spring 12. When

95 the driver desires to cut down the illumination to a flat topped beam he is enabled to 100 cause the screen 5 to slide into the closed forward position shown in Figure 1. For

105 this purpose a forked lever 13 with its fulcrum at 14 below the tubular shell 8 is arranged to press upon the rear surface of a flange 15 on the sleeve 10 against which also the spring 12 abuts. The lever 13 has a short arm 16 connected to a Bowden wire 17.

110 Thus when the latter is pulled the forked lever 13 pushes forward the screen 5 115 as shown in Figure 1.

120 In Figures 4 to 6, a slight modification of the invention is illustrated, the arrangement being such that the half barrel shaped screen 5 instead of being capable of being

125

130

withdrawn through the back of the reflector is arranged to move forwardly into the position shown in chain lines at 5^a.

In Figure 5 the operating and guiding mechanism is arranged substantially as follows:—A pair of guide rods 18 extend forwardly from the back of the lamp above the bulb 2. A pair of brackets with eyes 19 secured to the screen 5 extend upwardly so that the eyes embrace the rods 18. A bridge bar 20 extends between the front ends of the rods 18 and makes the whole arrangement rigid. A tension spring 21 has its fixed end anchored to the bridge bar 20 and its rear movable end to a pin 22 extending upwardly from the screen 5. The normal effect is for the spring 21 to contract and draw forward the screw 22 and the screen 5 into the forward position. However, a Bowden wire 17 is provided also attached to the pin 22 and arranged when operated to draw back this pin and the screen 5 to the "closed" position shown in full lines in Figure 4 and at the same time stretching the spring 21. The position of the filament 3 is substantially the same as shown in Figures 1 and 2 so that when the screen 5 is in the rear position the direct light from the filament is cut off from the upper part of the reflector 1, whereas when the screen 5 is allowed to move into the forward position, the reflector projects a substantially full or complete beam. When the screen is in the "open" position the shadow bars produced in the full beam by the guide rods 18 and spiral spring 21 can be diffused and obliterated by the use of a vertically grooved or ribbed front glass. In this figure a lamp bulb of elongated form is shown at 2^a, such form of bulb being preferable when employing higher candle power lamps for the reason already stated.

In the form of lamp illustrated in Figures 7 and 8, the screen 5 comprises a pair of folding leaves 5^a, 5^b pivotally mounted about a hinge 23. The screen is shown in the "open" position in full lines in Figure 7, in the "closed" position in Figure 8 and in the "open" position shown in Figure 9, whereas the "closed" position is shown in chain lines in Figure 7. It will be noticed that the axis of the hinge 23 lies in the vertical axial plane of the reflector 1. The front end of the hinge axis is approximately on the line 24 which joins the front end of the filament 3 to the mouth 25 of the reflector 1 and this front end of the hinge axis lies somewhat further from the axis of the reflector 1 than half the diameter of the bulb 2. The hinge axis extends from its front point to the reflector 1 along a line lying in the said vertical axial plane which is approximately normal to the surface of the reflector 1 at the point where the axis meets the reflector.

When the two leaves are in the "closed" position they are folded over the upper half of the hub to form a flat sided hood shaped cover, as can be seen from Figures 7 and 8, so that their outer edges rest substantially in the horizontal axial plane of the reflector in lines in that plane which correspond with the line of the hinge axis in the vertical axial plane. The rearward edges 26 of the leaves 5^a, 5^b are curved outwardly slightly to meet the surface of the reflector 1 when in the "closed" position and the forward edges 27 of the leaves may be curved inwards slightly, these forward edges at any point lying on the line from the front end of the filament 3 to the mouth 25 of the reflector. When in the "open" position the two leaves are folded so that they lie close together near to the vertical axial plane of the reflector as clearly seen in Figure 9. The leaves 5^a, 5^b may also be silvered and polished wholly or partly on the side next to the filament and it will be found that the light reflected from them when in the "closed" position produces increased lighting on the roadway near to the car. In this case also the leaves may be perforated to allow some light to pass, or they may be reduced in size or shape to allow a band of light to pass to the reflector at either their front or back edges or both.

The mechanism employed for causing the leaves 5^a, 5^b to fold into the "closed" position is as follows:—A mechanism plate 28 say one-sixteenth of an inch thick is formed with a hole of the diameter of the body of the lamp holder 7 and passes over the lamp holder 7 upon which it is clamped by a nut 29 against the back surface of the rear portion of the reflector 25. The mechanism plate 28 has formed in it a pair of arc-shaped slots 30 above an opening or hole in the wall of the reflector 1. The leaves 5^a, 5^b each carry an actuating member 31 which has a flat portion by means of which it is riveted to the respective leaf and a rearwardly projecting pin 32 which extends out through one of the slots 30. The slots 30 are circular so that when the blades turn about the hinge 23 the pins 32 pass along the slots 30.

The mechanism plate 28 has lateral turned over portions 33 which serve to form a guide for a further plate 34 arranged to slide up and down on the back surface of the plate 28. The plate 28 at its upper edge has a turned over part 35 and the plate 34 has a corresponding turned over part 36. An upwardly extending stem 37 is fixed to the part 36 of the plate 34 and passes through a hole in the part 35 of the fixed mechanism plate 28 and thus serves as an additional guide for the sliding plate 34. A helical spring 38 surrounds the stem 37 abutting at its lower end on the fixed part 130

35 of the mechanism plate and at its upper end against a washer 39 fixed on the upper end of the stem 37. Thus normally the spring 38 presses the stem 37 to its upper 5 limit and maintains the sliding plate 34 in its uppermost position. The latter, however, can be drawn downwardly from the driver's seat by means of a Bowden wire 17 secured to the washer 39 carried by the stem 10 37, thus compressing the spring 38. Immediately the Bowden wire mechanism is released the spring 38 thrusts the plate 34 again into its uppermost position.

The function of the plate 34 is to cause 15 the pivotal movement of the blades 5^a, 5^b and to that end the plate 34 has a pair of slots 40 through which the pins 32 also project. The slots are in the main horizontal although their inner ends are inclined downwards somewhat. Thus when 20 the spring 38 pushes the plate 34 to its uppermost position the slots 40 cause the pins 32 to be pushed inwards and the inclined inner parts of the slots ensure that 25 the blades 5^a, 5^b are held firmly in contact in the position shown in Figure 9. On the other hand, when the Bowden wire mechanism draws down the plates 34 the pins 32 tend to fall downwardly in the slots 30 and, of course, the slots 40 allow of that 35 movement so that when the blades reach the full "closed" position the pins 32 have reached the bottom of the slots 30.

In the form of lamp shown in Figures 35 10 and 11 the screen 5 is a hood shaped cover in the form of a segment of a spherical surface. The front edge 41 is straight as seen in Figure 11 and surrounds the bulb fairly closely while the rear edge 42 has a 40 concave curvature. The reflector 1 has a curved slot 43 shaped to correspond to the curvature of the screen 5 and as the latter is mounted about a pivot 44 it is capable of passing out through the slot 43 into the 45 "open" position indicated in chain lines in Figure 10 at 5^a. In the "closed" position shown in full lines in Figure 10 the screen 5 is substantially within the reflector 1, its front edge 41 lying approximately on the 50 line 24 joining the front end of the filament 3 to the mouth 25 of the reflector 1. The screen 5 has at one side, as clearly seen in Figure 11, a cylindrical boss 45 rigidly fixed to it as by riveting or brazing and integral 55 with this boss is a double armed lever 46. The boss 45 is journalled on the axis 44 about which the screen turns and the rear arm of the double armed lever 46 is anchored to a tension spring 47 fixed at its 60 other end to a downwardly projecting fixed bracket 48. Thus the normal tendency of the spring 47 is to draw the screen 5 into the "open" position, that is the position shown in chain lines in Figure 10. However, 65 a Bowden wire 17 is fixed to the forward

arm of the lever 46 and when operated from the driver's seat draws this forward arm downwards and rocks the screen 5 into the "closed" position shown in full lines in Figure 10.

Referring now to Figure 12, a form of lamp is shown which is similar to that shown in Figures 1 to 3 and 4 to 6 in that the screen is a half barrel shaped or semi-cylindrical screen which is in fact arranged 70 to be moved rearwardly to the outside of the reflector 1 and the construction is similar to that shown in Figures 10 and 11 in that the screen 5 is rocked about a horizontal transverse axis 44, although in this case the axis 44 does not intersect the central axis of the reflector 1, but is situated towards the top of the lamp and approximately above the central plane of the screen 5 when the latter is in the "closed" position. 75 The screen 5 is shown in the "closed" position in full lines and is shown in the "open" position in chain lines at 5^a. It is carried upon an arm 50, which latter has an inturned portion 51 secured to the rear of the screen 5. In this case also the screen is operated 80 by a Bowden wire 17 and is returned to the "open" position outside the reflector 1 by a tension spring 52. It is not necessary to state further particulars of the form 85 shown in Figure 12 as these can be readily appreciated from the study of the construction shown in Figures 1 to 3 and 10 and 11.

If the movable screen 5 is shortened a narrow angle rising light half beam will be 90 produced above the centre of the flat topped beam of a width and intensity depending on the amount of shortening of the movable screen. If the movable screen is shortened 95 on one side only of the vertical axial plane 100 a narrow angle quarter beam will be produced and if the movable screen is cut away entirely on one side a full three quarter beam will be obtained. Again, by suitably perforating the movable screen a subdued rising 105 light half beam will be produced and if these 110 perforations are confined to one side of the central axial plane only, a subdued rising light quarter beam will be obtained, or by 115 suitably perforating both sides rising light each side.

Any form of concentrated light source 120 may be used with the arrangement though a single pillar incandescent filament focussed as described is the preferred form. For instance, a double pillar filament or V-shaped filament may be used or even a pillar filament mounted to lie across the axis of the reflector can be focussed to produce a fair 125 result.

An electric lamp bulb having an attachment secured to the lamp cap which engages a lamp holder mounted in a standard position relatively to the surface of the reflector 130

is particularly useful in combination with the devices herein described and such a combination constitutes a part of the present invention. An electric lamp bulb having a fitting piece for focussing bulbs of the form set forth in the specification of my British Patent No. 204,774 and employed with a special lamp holder in accordance with the specification of my British Patent No. 204,464

5 are particularly suitable for use with this invention. The lamp holder 7 shown in all of the examples illustrated is a lamp holder of this type and it will also be noted that in each case the lamp bulb employed is shown

10 with a fitting piece 49 of the kind just referred to.

Having thus described my invention, what I claim as new and desire to secure by Letters Patent is:—

20 A headlamp for motor vehicles comprising a lamp body, a parabolic reflector mounted therein, a source of illumination extending

from the focus of said reflector along its axis, a movable screen mainly formed as a zone from the central portion of a hemisphere and polished and plated on its inner surface, and so disposed that, when the screen is in the operative position, the centre of the sphere lies approximately on the axis of the reflector and between the centre of 25 the light source and that end of it which is farthest from the focus of said reflector and an actuating mechanism operatively connected to said screen to cause the latter to move between its two extreme positions—one in 30 which it intercepts the rays from said source of illumination to or from substantially one half of said reflector and the other in which it allows the light free access to substantially 35 all of said reflector.

40 In witness whereof, I hereunto subscribe my name this 3rd day of May, 1926.

HAROLD WORKMAN.
